UNITED STATES PATENT OFFICE.

CHARLES W. SAXE, OF WORCESTER, MASSACHUSETTS, ASSIGNOR TO NORTON COMPANY, OF WORCESTER, MASSACHUSETTS, A CORPORATION OF MASSACHUSETTS.

REFRACTORY MUFFLE.

Application filed July 3, 1926. Serial No. 120,466.

This invention relates to structures employed as muffles or as combustion chambers in furnaces and particularly to that type of muffle or combustion chamber described in the U. S. patent to Meehan No. 1,348,511 and referred to throughout this specification as a muffle structure.

It has been common heretofore to make structures of this type from a refractory granular material, such as silicon carbide or fused crystalline alumina, united by an appropriate ceramic bond. In accordance with this practice the granular material is mixed with the required amount of a suitable ceramic bond, such as fire clay, together with a fluid, such as water, to impart the desired plasticity to the mass. The plastic mixture is then carefully placed in a cored plaster mould and permitted to dry, after which the moulded article is removed and fired to vitrify the bond. This method of manufacture not only has been extremely difficult but has been very expensive. Furthermore, muffles manufactured in this manner have been subject to warpage during firing causing strains to be set up in the structure which often result in breakage.

It is the object of the present invention to provide a muffle of simplified construction which may be manufactured at small cost and which is suitable for high temperature operations.

It is another object to provide a muffle construction in which the top and bottom plates are interchangeable as well as the plates forming the side walls of the muffle thereby reducing the number of differently shaped plates to a minimum.

In accordance with the invention a muffle is provided by assembling dense refractory plates constructed so that the plates for the top and bottom portions are interchangeable and have a length equal to the width of the finished structure, and the interchangeable plates for the side portions extend between the top and bottom portions and are held by the bottom portion and support the top portion. Each plate is provided with a relatively large engaging surface containing a tongue or groove so that the plates may be fitted together to form self supporting integral muffle walls. Preferably, the refractory plates are made of a dense structure by tamping with considerable pressure

prior to firing the articles to vitrify the bond.

The invention will be more clearly understood from the following description in conjunction with the accompanying drawing: in which,

Fig. 1 is a perspective view of the structure of the invention;

Fig. 2 is a detail perspective view of a plate employed in the side portions of the structure;

Fig. 3 is a detail view in perspective of a plate employed in the top or bottom portions of the structure; and

Fig. 4 is a sectional elevational view of a furnace embodying the structure of the invention.

In the drawing, a structure is illustrated embodying the invention comprising a plurality of dense, flat refractory plates forming the bottom portion 10 carrying a plurality of interchangeable vertically positioned plates of similar material forming side portions 11 which support a plurality of plates of refractory material forming the top portion 12. The bottom and top portions of the structure are interchangeable and are formed by interfitting a plurality of plates 13 having a length equal to the width of the finished structure. A groove 14 is formed in one longitudinal edge of the plate 13 and a tongue 15 is provided upon the opposite longitudinal edge and is constructed and arranged to engage the groove 14 of any similarly constructed plate.

The flat face of the plate 13 is provided with a lateral groove 16 arranged to receive a tongue 17 on the relatively wide flat edge 18 of a refractory plate 19. One of the lateral edges of the plate 19 is provided with a groove 20 and the other is provided with a tongue 21 so that a plurality of the plates may be fitted together to form the side portions 11. The bottom portion of the structure is formed by interfitting a plurality of the plates 13 by engagement of the tongue 15 with the groove 14 on the next adjacent plate. The plates 19 are then fitted together by forcing the tongue 21 into the groove 20 in the next adjacent plate, and as thus assembled are placed upon the bottom portion 10 so that the tongues 17 may be forced into the grooves 16. The top portion 12 is then formed by interfitting a plurality of plates

13 by engagement of the tongue 15 with the groove 14 of adjacent plates, and as thus assembled is placed in position upon the structure so as to bring the tongues 17 on the plates 19 into engagement with the grooves 16 upon the plates 13. In this manner a self-supporting structure is produced which is adapted to effectively resist the heat changes to which a muffle is normally subjected.

The refractory plates 13 and 19 may be made of any suitable refractory material, such as silicon carbide or crystalline fused alumina. This material is mixed with a suitable vitrifiable ceramic bond and an amount of water just sufficient to impart moldability to the mixture. The mixture is then placed in a suitable mold and tamped with considerable pressure or impact. The molded article is then removed and dried before placing in a kiln or firing to vitrify the bond.

The structure of the invention may be employed either as a combustion chamber or as a muffle in a furnace construction, such as is diagrammatically illustrated in Fig. 4, comprising a floor 25 and sidewalls 26 which support a top 27, the ends being closed by a door or end wall 28. The structure of the invention may be placed within the furnace so that it rests above the floor 25 preferably with the bottom portion supported, as by pillars 29, so as to provide free circulation of heat or gases around the structure.

In practice, the furnace may be fired by the combustion of fuel within the furnace but outside of the muffle so that the gases will not come directly in contact with the contents within this structure. So also, the firing conditions may be reversed and the structure of the invention may be employed as the combustion chamber in which the fuel is burned to transmit heat to the other parts of the furnace.

The invention provides a muffle of simple construction which may be manufactured at a low cost, and while it is composed of a plurality of separate sections, nevertheless, it is self-supporting and will not warp ap-

preciably under normal conditions of high temperature operations.

50 Staggering of the edges of adjoining plates assists in preventing distortion and warpage. The provisions of the invention permit the building of relatively long muffles, and if any of the plates become over-heated they may be easily replaced.

Having thus described my invention, what I claim as new and desire to secure by Letters Patent is:

1. A refractory muffle structure for use 60 in high temperature furnace operations comprising a plurality of flat dense refractory plates having a length equal to the width of the structure and provided with tongues and grooves interfitting to form continuous 65 top and bottom walls of the muffle, and a plurality of plates of similar material extending between the top and bottom which are provided with tongues and grooves interfitting to form the muffle sides, said side 70 plates being arranged upon the bottom plates and adapted to support the top plates and provided with wide flat edges containing tongues adapted to engage grooves in the inner flat surfaces of the top and bottom 75 plates, thereby providing an integral self supporting structure adapted to effectively resist the heat changes encountered in high temperature operations.

2. A refractory muffle structure for use 80 in high temperature furnace operations comprising a plurality of interchangeable flat dense refractory plates forming the top and bottom of the muffle, and interchangeable side plates supported on the bottom plates 85 and in turn supporting the top plates, each of the top and bottom plates extending the full width of the muffle and the side plates extending between the top and bottom of the muffle, said plates having interfitting tongue 90 and groove connections to form self supporting muffle walls.

Signed at Worcester, Massachusetts, this 1st day of July, 1926.

CHARLES W. SAXE.
